UNITED STATES PATENT OFFICE.

HARRY H. BASSETT, OF FLINT, MICHIGAN.

DESIGN FOR A RADIATOR CASING FOR AUTOMOBILES.

Application filed March 24, 1923. Serial No. 5,584. Term of patent 14 years.

To all whom it may concern:

Be it known that I, HARRY H. BASSETT, a citizen of the United States, and a resident of Flint, county of Genesee, and State of Michigan, have invented a new, original, and ornamental Design for Radiator Casing for Automobiles, of which the following is a specification, reference being made to the accompanying drawing forming a part thereof.

In the drawing the figure shows my new design for radiator casing for automobiles in front elevation.

I claim:

The ornamental design for a radiator casing for automobiles substantially as shown.

HARRY H. BASSETT.
